SLUSH PUMP SEAL RING

William E. Pielop, Jr., Houston, Tex.

Application April 21, 1951, Serial No. 222,225

4 Claims. (Cl. 309—23)

1

This invention relates to a seal ring for use in pumps such as slush pumps. Slush pumps are used generally for the pumping of drilling mud in the rotary method of drilling wells and in the past considerable difficulty has been experienced with the seal rings on these slush pumps when pumping viscous and abrasive mud wherein pressures of 2,000, 3,000 and 4,000 pounds per square inch and even greater pressures may be maintained.

Under such high pumping pressures, it has been found that one of the most critical causes of failure in pumping mud with slush pumps has been in the construction of the slush pump seal rings. Tearing and splitting of the seal ring body as well as loss of pressure in the pump due to excessive peripheral wear on the seal ring are among the many and varied problems by those in the field.

It is therefore one of the objects of this invention to provide a slush pump seal ring which has reduced tendencies to tear and split on the seal ring body and to wear on the peripheral surface thereof during pumping of drilling mud.

Another object of this invention is to provide a seal ring of resilient material and a reinforcing dish entirely enclosed within the resilient material.

A further object of this invention is to provide a seal ring which has a resilient cylindrical body with a flared lip for engaging a pump cylinder and a reinforcing dish entirely within the body and below the flared lip so that rigidity will be provided for the base while retaining the resilient peripheral flare wear surface of the flared lip.

An additional object of this invention is to provide a slush pump seal ring wherein a circular reinforcing dish is utilized, which dish has a plurality of studs thereon and a plurality of holes therein alternately spaced with respect to said studs.

A still further object of this invention is to provide a slush pump seal ring which has a resilient base and a resilient flared lip integral therewith and a flat internal shelf on the base to receive a retainer ring and a reinforcing dish which has studs thereon and holes therein in alternate relationship, the reinforcing dish being located entirely within the resilient base.

Other and further objects of this invention will be readily apparent when the following description is considered in connection with accompanying drawings wherein:

Fig. 1 is a top view of the reinforcing dish illustrating the alternate relationship of the studs and holes.

2

Fig. 2 is a section of the reinforcing dish on line 2—2 of Fig. 1.

Fig. 3 is a section of the complete seal ring showing the reinforcing dish on the same section as that shown in Fig. 2.

Referring now to the details of the drawings wherein like reference numerals indicate like parts in all figures, Fig. 1 and Fig. 2 show the reinforcing dish 10 which is circular in shape and is formed by a skirt 11 and flat bottom 12. A curved section 15 is located between the flat bottom 12 and skirt 11 to form the complete integral reinforcing dish 10. Within said flat bottom is a central opening 16. Positioned on the flat bottom 12 adjacent central opening 16 are three reinforcing studs 17. These studs 17 may be made integral with the reinforcing dish 10 or may be welded or otherwise fixed to dish 10; however, it is preferable to form the reinforcing dish 10 by forging it from metal and therefore welding of the studs 17 to the dish 10 after the forging operation has been found to be the most satisfactory in service. It should be pointed out that metal is the most desirable material for the reinforcing dish 10 and studs 17; however, it can readily be appreciated that other materials such as synthetic plastics may be used if sufficient strength can be obtained for use as a reinforcing member of the dish 10.

As can be seen in Fig. 1, the studs 17 are flush with the inner edge 18 of the flat bottom 12; thus, as best shown in Figs. 2 and 3 the cross-sectional area of the reinforcing dish 10 and any one of the studs 17 together form a U-shaped section.

Equally spaced between the three studs 17 are three openings or holes 20. These openings 20 are alternately spaced in relationship to studs 17. The purpose of these holes 20 is to provide an area for the resilient material of the cylindrical body 30 to pass through in order to lock the reinforcing dish 10 to the cylindrical body 30. It can be readily appreciated that by having rubber or other resilient material in holes 20 that the integralness of the dish 10 and resilient body 30 will be greatly improved. Also, the tendency of the dish 10 to rotate or slide within the body 30 is prevented. Of course, the studs 17 also serve to prevent rotation or sliding of dish 10 to some extent. It is to be understood that this invention is not limited to the use of three studs 17 and three holes 20, but it is preferable to have a plurality of the holes 20 and the studs 17.

The resilient cylindrical body 30 may be made of rubber, synthetic or natural, or any other synthetic materials, but for most purposes natural

rubber has been found superior in performance. Resilient cylindrical body 30 is an integral body having the reinforcing dish 10 molded therein. The reinforcing dish 10 is located entirely within the cylindrical body 30 and more particularly, this reinforcing dish 10 is located in the annular resilient base 22. This base 22 is substantially rectangular in cross-sectional area. Inwardly of the base 22 is a central opening 23 in the cylindrical body 30. The piston flange side 24 of the base 22 is substantially flat. On the opposite side of the base 22 from the flange side 24 is an outwardly flared lip 28 which is of larger outside diameter than the outside diameter of the base 22 and of considerably larger inside diameter than the inside diameter of the base 22; thus, flared lip opening 31 is of greater diameter than the diameter of the central opening 23.

When the slush pump seal ring of this invention is in its normal use, it is fitted on a piston shaft, not shown, which passes through the opening 23. A piston flange, not shown, on the piston shaft abuts the flange side 24 of the seal ring body 30. To prevent the seal ring from slipping off the piston shaft in use, a retainer plate fits against an inner shoulder or retainer plate shelf 35. The inner shoulder 35 is substantially parallel to flange side 24 of base 22 and is positioned at the junction 36 of lip 28 and base 22. Shoulder 35 merges with the inner inclined surface 38 of flared lip 28 and the inclined surface 28 in turn merges with the inner beveled surface 41. Details of a pump shaft and flange which may be used can be found in my copending application 56,835, filed October 27, 1948 now Patent No. 2,600,516.

From Fig. 3, it can be seen that skirt 11 of the reinforcing dish 10 extends adjacent to the junction 36 of lip 28 and base 22. The skirt 11 also runs substantially parallel to the annular peripheral surface 42 of the seal ring body 30. The annular peripheral surface 42 of seal ring body 30 is formed by the merger of the annular peripheral surface 43 of base 22 and the annular peripheral surface 45 of flared lip 28. The annular peripheral surface 45 of lip 28 forms an outwardly sloping angle from the annular peripheral surface 43 so as to obtain the flared effect necessary to provide positive sealing by lip 28 with the inside of a pump cylinder, not shown. The studs 17 are generally slightly shorter than the upper edge of skirt 11, but this invention is not so limited; it is desirable to have the upper part of skirt 11 substantially the same height as the studs 17. Thus, rigidity and integralness can be obtained in the base 22 while maintaining flexibility of the flared lip 28 which serves to increase the wear life of the seal ring of this invention.

The studs 17 preferably fit just below inner shoulder 35 so that there is a narrow section 51 of rubber just above studs 17. On the inner surface of studs 17 is a narrow section 52 of rubber. It can thus be seen that reinforcing dish is entirely within resilient body 30 but is sufficiently close to the piston flange side 24, inner shoulder 35 and inner peripheral surface 55 so that a cushioned rigidity is obtained by the seal ring when it is positioned on a piston shaft and flange. Heretofore, these desirable properties and characteristics have been unobtainable; this new combination of structural features results in a cooperation which has given increased wear life and outstanding performance in the field, particularly in connection with slush pumps.

Broadly, this invention contemplates a flared

lip seal ring with a reinforcing dish integrally secured entirely within the seal ring body.

What is claimed is:

1. A seal ring for slush pump pistons comprising, a cylindrical resilient body, a central opening in said body, said body comprising an annular resilient base and an annular resilient lip thereon, an internal shoulder formed at the junction of said base and said lip to provide a surface for receiving a retainer plate, annular peripheral surfaces on each of said base and said lip which surfaces merge into a unitary peripheral surface, an outwardly flared portion at the upper end of said lip so that the inherent resiliency of the ring material maintains said lip flared into contact with a pump piston cylinder, a reinforcing dish embedded entirely within the resilient material composing said ring comprising a metal forging having a generally tubular skirt concentric with the outer periphery of said ring and having a flat bottom, said skirt extending substantially parallel to said annular peripheral surface to rigidify said peripheral surface and extending upwardly from said bottom to a level adjacent said junction so that the resiliency of said flared lip is maintained, a plurality of angularly spaced studs projecting upwardly from said bottom, the cross-sectional area of said studs and said reinforcing dish together forming a U-shaped area.

2. A seal ring for slush pump pistons comprising, a cylindrical resilient body, a central opening in said body, said body comprising an annular resilient base having a substantially flat inner end and provided with an annular resilient lip at its outer end, an internal shoulder formed at the junction of said base and said lip to provide a surface for receiving a retainer plate, annular peripheral surfaces on each of said base and said lip which surfaces merge into a unitary peripheral surface, a flared portion at the upper end of said lip so that the inherent resiliency of the ring material maintains said lip flared into contact with a pump piston cylinder, a reinforcing dish embedded entirely within the resilient material composing said ring comprising a metal forging having a generally tubular skirt concentric with the outer periphery of said ring and having a flat bottom, disposed substantially parallel with said inner end of the base said skirt extending substantially parallel to said annular peripheral surface to rigidify said peripheral surface and extending upwardly from said bottom to a level adjacent said junction so that the resiliency of said flared lip is maintained, a plurality of angularly spaced studs projecting upwardly from said bottom, the cross-sectional area of said studs and said reinforcing dish together forming a U-shaped area, said studs extending adjacent and below said internal shoulder, spaced openings in said dish intermediate said studs, and resilient material of said body molded through said spaced openings to improve the integralness of said body and said reinforcing dish.

3. A reinforcing dish for a slush pump seal ring comprising a cylindrical metal body composed of a generally tubular skirt and a flat bottom integral therewith, a central opening in said bottom, a plurality of angularly spaced studs connected with said bottom adjacent said central opening, and extending upwardly therefrom generally parallel to said skirt and to a height substantially level with the upper end of said skirt and a plurality of holes in said dish.

4. A seal ring for slush pump pistons comprising

ing, a cylindrical resilient body, a central opening in said body, said body comprising an annular resilient base having a substantially flat inner end and provided with an annular resilient lip about its outer end, and internal shoulder formed at the junction of said base and said lip to provide a surface for receiving a retainer plate, annular peripheral surfaces on each of said base and said lip which surfaces merge into a unitary peripheral surface, a reinforcing dish embedded entirely within the resilient material composing said ring comprising a rigid body having a generally tubular skirt to face outwardly in said ring and having a flat bottom disposed parallel to said flat inner end of said base, said skirt extending substantially parallel to said annular peripheral surface to rigidify said peripheral sur-

face and extending upwardly from said bottom to an elevation adjacent said junction so that the resiliency of said lip is maintained, a plurality of angularly spaced studs projecting upwardly from said bottom, the cross-sectional area of said studs and said reinforcing dish together forming a U-shaped area.
